UNITED STATES PATENT OFFICE

GEORGE E. PRIEST, OF SYRACUSE, NEW YORK

BUILDING STAVE

Application filed January 7, 1930. Serial No. 419,036.

This invention relates to sectional structures and more particularly to staves for bins, silos and the like.

It has been the practice in the past to construct bins or silos of sectional staves formed of concrete or other similar plastic material, but much difficulty has been encountered due to the fact that these staves were improperly designed to withstand strains and stresses to which they were subjected in use. This difficulty has existed in spite of the fact that these staves have included an excessive amount of concrete with the resultant increase in cost of material and the additional expense entailed in handling and shipping them.

In accordance with the present invention a novel stave has been produced which furnishes the required tensile strength at the points most needed to avoid cracking of the staves when the hoops are tightened or when maximum loads are applied either from loading the bin or silo itself or from wind pressure. The present design of stave is strong enough to carry maximum loads and light enough because of the small amount of concrete used so that shipping weight and labor in handling permit prices to meet competition. One of the main features of the invention consists in increasing the thickness and contact area of both sides of the stave where the hoop bears and in shortening the span between hoop bearings, so that the load bearing on both edges of the stave is equalized. A further feature of the invention consists in providing the outer surface of each stave of undulating or wavy contour so that there are shorter spans between hoop contacts and a greater area of concrete under compression to support a maximum load while there is a total reduction in weight of concrete in each stave over that now used.

These and other features will appear from the detailed description and claims when

taken with the drawings in which Fig. 1 is a side elevation of a portion of a bin or silo formed of the staves of the present invention; Fig. 2 is a top view of a section of such a bin or silo; Fig. 3 is a front elevation of the present stave; Fig. 4 is a side elevation thereof and Fig. 5 is a cross sectional view of the stave of Fig. 3 taken on the line 5-5; while Fig. 6 is an end or top view of a stave, and Figs. 7 and 8 are cross-sectional views of such a stave taken respectively on the lines 7-7, 8-8 of Fig. 3.

In Fig. 1, 10 generally designates a section of a bin or silo comprising a suitable foundation 11 on which there are mounted a series of staves 12 and 13 in interlocking relation and held in place by hoops 19. It will be noted that the staves 12 and 13 are of unequal length so that joints between laterally adjacent staves do not come together. By reference to Figs. 4 and 5 it will be noted that the top of each stave is provided with a groove 14 while the bottom thereof is provided with a tongue 15 so that the tongue of one stave may engage the groove of an adjacent stave. Similarly each stave is provided with a lateral groove 16 and a lateral tongue 17 so that adjacent staves may interlock. It has been found through extensive use of concrete staves that a great deal of breakage occurs at about five inches from any unreinforced corner.

I have discovered that breakage may be reduced to a minimum and the total weight of each stave reduced if each edge of the stave is provided with a series of projections or hoop bearing portions 20 to 25 inclusive. Each such bearing portion slopes to the main body of the stave and the base of each projection or bearing portion merges into the body and into the base of the adjacent projections so that the base of such portion is relatively large in area so that a rather large amount of concrete is under compression. By reference to Figs. 3 to 8 inclusive it will

be noted that these hoop bearing portions are so disposed that the face of the stave has an undulating contour vertically and horizontally of the stave. It will further be seen that the groove 26 is relatively wide so that it will be engaged by the hoop even though the stave is somewhat warped as sometimes occurs. Furthermore, the bottom of the groove 26 is so shaped that longitudinally it engages a considerable portion of each hoop. In addition the spans between adjacent contacts 20 and 21 or 22 and 23 are so short (being less than twice the length of groove 26 in Fig. 7) that the stave is not materially weakened although its volume and weight are considerably reduced. In effect the contour of the stave is such that it employs the principle of the flat slab and beam construction with the result that a maximum amount of concrete is used where the load is applied without unduly increasing the weight of the stave so that a durable, commercial stave is provided.

What I claim is:

- 25 1. A building stave comprising a body and integral projections on one side thereof along opposite sides of the median line of the body, between said median line and the side edges of the body, said projections on each side of said line being paired with, and arranged in horizontal alinement with, those on the other side of the line and being tapered from their bases toward their outer ends and having hoop receiving seats at their outer ends, the base of each projection merging in the body and into the base of the adjacent projections, whereby the force applied to the said projections by the hoop is distributed throughout the body.
- 30 2. A building stave comprising a body and integral projections on one side thereof along opposite sides of the median line of the body between said median line and the side edges of the body, said projections on each side of said line being paired with, and arranged in horizontal alinement with, those on the other side of the line and being tapered from their bases toward their outer ends and having hoop receiving seats at their outer ends, the base of each projection merging in the body and into the base of the adjacent projections, the bases also extending to the lateral edges of the stave, whereby the force applied to the said projections by the hoop is distributed throughout the body.
- 35 3. A reinforced concrete building stave having integral hoop contacting projections on its outer face and arranged along the lengthwise margins thereof on opposite sides of the median line of the stave, the projections on each side of said line being paired with those on the other and arranged in transverse alinement therewith, the base of each projection merging into the body and into the base of the adjacent projections, and hav-

ing hoop seats at their outer contacting ends, whereby the pressure applied by the hoops is distributed throughout the body, and the body having internal reinforcing bars embedded therein and extending vertically and transversely thereof, the transverse bars being located in the body midway between the apices of the projections.

In witness whereof, I hereunto subscribe my name this 2nd day of January A. D. 1930.

GEORGE E. PRIEST.
